(57) **CLAIM**

The ornamental design for a display screen or portion thereof with graphical user interface as shown and described.

DESCRIPTION

FIG. 1 is a front view of a display screen or portion thereof with graphical user interface according to a first embodiment of the claimed design.

FIG. 2 is a front view of a display screen or portion thereof with graphical user interface according to a second embodiment of the claimed design.

FIG. 3 is a front view of a display screen or portion thereof with graphical user interface according to a third embodiment of the claimed design.

FIG. 4 is a front view of a display screen or portion thereof with graphical user interface according to a fourth embodiment of the claimed design.

FIG. 5 is a front view of a display screen or portion thereof with graphical user interface according to a fifth embodiment of the claimed design; and,

FIG. 6 is a front view of a display screen or portion thereof with graphical user interface according to a sixth embodiment of the claimed design.

The dash-dot-dash broken lines in the drawings illustrate boundaries of the display screen or portion thereof and environmental matter that form no part of the claimed design.

The lighter weight dash-dash broken lines in the drawings illustrate portions of the graphical user interface and environmental matter that form no part of the claimed design. The heavier weight dash-dash vertical broken lines at the side portions of the graphical user interface in FIGS. 1-4 of the drawings are claimed.

In FIGS. 1-4 of the drawings, the stipple shading represents translucency of portions of the graphical user interface. No particular color of the translucent portions is claimed.

In FIGS. 1 and 2 of the drawings, the cross-hatch patterning is claimed.

The broken line medical images shown layered beneath the graphical user interface portions in the drawings form no part of the claimed design. The broken line medical images are visible through the translucent portions of the graphical user interface.

In FIGS. 5 and 6 of the drawings, the lighter stipple shading at the upper-left section of the graphical user interface represents a first translucent appearance, the heavier stipple shading at the lower-left section of the graphical user interface.

(Continued)

interface represents a second translucent appearance, and the alternating heavier and lighter stipple shading at the central-left section of the graphical user interface between the upper-left section and the lower-left section represents a third translucent appearance, although no particular colors are claimed.

In FIGS. 5 and 6 of the drawings, the cross-hatch patterning at the upper-right section of the graphical user interface, the cross-hatch patterning at the lower-right section of the graphical user interface, and the cross-hatch patterning at the central-right section of the graphical user interface is claimed.

Portions of the unclaimed medical images are visible through the openings formed by the cross-hatch patterning.

1 Claim, 6 Drawing Sheets
